UNITED STATES PATENT OFFICE.

GUSTAV B. PETSCHE, OF YONKERS, NEW YORK.

ROTARY PUMP.

1,397,699.

Specification of Letters Patent.

Patented Nov. 22, 1921.

Application filed October 6, 1920. Serial No. 415,142.

To all whom it may concern:

Be it known that I, GUSTAV B. PETSCHE, a citizen of the United States of America, and resident of Yonkers, in the county of 5 Westchester, State of New York, have invented a certain new and useful Improvement in Rotary Pumps, of which the following is a true and exact description, reference being had to the accompanying drawings, 10 which form a part thereof.

My invention relates to rotary compressors of the type in which the piston consists of an eccentric ring actuated by an eccentric on the driving shaft and provided with an ex- 15 tension which forms a partition between the ports. The object of my invention is to provide such a pump with a delivery valve actuated to open by the building up of pressure in the cylinder and actuated to close by a 20 positively driven cam.

The nature of my improvements will be best understood as described in connection with the drawings in which they are illustrated as applied to a grid iron slide valve 25 and in which—

Figure 1 is a side elevation taken on the section line 1—1 of Fig. 2.

Fig. 2 is a front view partly in section on the broken line 2—2 of Fig. 1.

Fig. 3 is a plan view partly in section on the line 3—3 of Fig. 1.

Figs. 4 and 5 are views showing modifications of the cams and cam actuated devices.

A and A' are two twin pump cylinders 35 formed in the same casing having face plates A² and A³. A⁴ indicates the cylindrical periphery of one of the pump chambers cut away from a' to a² to give clearance for the motion of the piston extension. B is the 40 bearing for the swivel block; B' the admission chamber and B² the receiving chamber. C is a delivery passage leading from the delivery end of the pump chamber to the receiver B²; C' being a port leading into the pump 45 chamber and C² the port leading into the receiver. D is the driving shaft to which are attached eccentrics as indicated at D'. E indicates the eccentric ring piston having an extension here shown as the slide F extending 50 from one side of it, the slide in the construction illustrated having a passage F' communicating with the admission chamber B' and with the port F² opening into the pump cylinder and arranged to be closed by the sides 55 of the swivel block when the piston is not in contact with the periphery of the cylinder.

G is a valve casing or bushing fitting in the chamber C and having a grid iron valve seat indicated at G'. H is a grid iron valve seated on this seat and having a stem H' to 60 which, as shown, is secured a piston H² and a cam contacting roller H³. I is a cylinder connected at one side with the port I' leading as shown from the port C' and connected on its other side by a port I² with the 65 receiver. J is a cam shaft having secured to it cams as indicated at J', the shaft J being driven through gear wheels K, K', shaft K² and gear wheels K³, K⁴, the last of which is secured to the rear end of the driv- 70 ing shaft at the pump. Preferably the cam shaft gearings are inclosed by casings indicated at L', L², so as to avoid the necessity of additional stuffing boxes with their possible leakage which is most objectionable 75 where poisonous gases are to be compressed. These casings should be charged with oil. O indicates the swivel block.

In Fig. 4 the cams indicated at M are secured to arms M' extending out from the 80 rock shaft M³ actuated through a lever arm M² and connecting rod M⁴ with a crank M⁵ on the shaft D and in Fig. 5 the cams indicated at N, N, are attached to a slide N' actuated through a link N² and lever N³ by 85 some connection with the driving shaft not shown.

In operation the gas in the admission chamber B' passes through the passage F' in the slide F and enters the receiving side 90 of the pump chamber through the port F², this port being closed by the surface of the swivel block at one period in the motion of the piston which coincides with the period when the piston is passing from contact at 95 a² to contact at a. These features of construction are new with me and covered in my co-pending application filed October 6, 1920, Serial No. 415,145, and form no part of my present invention. The air can, of 100 course, be admitted through any other admission port leading directly into the cylinder. It will be obvious that as the fluid in the compressor is propelled toward the delivery side of the cylinder by the piston the 105 pressure will build up in the port C' and on the under side of the grid iron valve H which is normally closed and held to its seat by the pressure in the receiver B². As the pressure builds up on the lower side of the 110 valve it is communicated to the left hand side of the cylinder I through the port I'

while the right hand side of the cylinder is in communication with the cylinder B² through the port I². At the time when the pressure on both sides of the valve is about 5 equal the pressure on the left of piston N² will open the grid iron valve permitting the fluid to flow into the receiver. The form and motion of the cams indicated at J is such that they will positively close the valve 10 at the end of the compressing cycle and the piston. This is very important irrespective of the kind of valve used or the means employed to open it, in view of the high speed with which compressions of the kind indicated are operated.

Having now described my invention, what I claim as new and desire to secure by Letters Patent, is:

1. In combination with a rotary compressor having a rotary eccentric ring piston provided with an extension forming a partition between the admission and delivery ports, a valve seat in the delivery port, a delivery valve operating with said seat to 20 open and close the port, a cylinder and piston for actuating said valve to open it, said cylinder being connected to the delivery side of the compressor and operating to open the valve when the pressure in the compressor attains a definite ratio to the pressure in the receiver, and a cam operating synchronously with the driving shaft of the compressor and formed to close the valve at the end of the compression cycle of the piston.
2. In combination with a rotary compressor having a rotary eccentric ring piston provided with an extension forming a partition between the admission and delivery ports, a grid valve seat located in the delivery port, a grid valve movable on said seat, a cylinder and piston for actuating said valve to open it, said cylinder being connected to the delivery side of the compressor and a cam operating synchronously 30 with the driving shaft and formed to close the valve at the end of the compression cycle of the piston.
3. In combination with a rotary compressor having a rotary eccentric ring piston provided with an extension forming a partition between the admission and delivery ports, a grid valve seat located in the delivery port, a grid valve movable on said seat, a cylinder and piston for actuating

said valve to open it said cylinder being 55 connected to the delivery side of the compressor and to the delivery chamber and a cam operating synchronously with the driving shaft and formed to close the valve at the end of the compression cycle of the 60 piston.

4. In combination with a rotary compressor having a rotary eccentric ring piston provided with an extension forming a partition between the admission and delivery 65 ports, a grid valve seat located in the delivery port, a grid valve movable on said seat, a cylinder and piston for actuating said valve to open it said cylinder being connected to the delivery side of the compressor, a cam for closing the valve, gears for 70 operatively connecting the cam with the driving shaft and a tight casing inclosing said gears.

5. In a rotary pump having a rotary eccentric ring piston and a slide extending from said piston through a swivel block, a delivery passage extending from the cylinder to a receiver a grid valve seat in said passage a grid valve movable on said seat 80 to open and close the passage, a cylinder connected at opposite ends to the delivery side of the pump and to the receiver, a piston working in said cylinder and operatively connected to the valve and a cam actuated synchronously with the driving shaft of the pump and operating on the valve to close it at the end of the compression cycle of the pump.

6. In a rotary pump having a rotary eccentric ring piston and a slide extending from said piston through a swivel block, an admission port and means for closing 90 said port during the period when the piston is not in contact with the periphery of the 95 cylinder, a delivery passage extending from the cylinder to a receiver, a grid valve seat in said passage, a grid valve movable on said seat to open and close the passage, a cylinder connected at opposite ends to the 100 delivery side of the pump and to the receiver, a piston working in said cylinder and operatively connected to the valve and a cam actuated synchronously with the driving shaft of the pump and operating on the valve 105 to close it at the end of the compression cycle of the pump.

GUSTAV B. PETSCHE.
